ATTORNEY

UNITED STATES PATENT OFFICE

GEORGE R. HOPPE, OF LOS ANGELES, CALIFORNIA

PROTECTIVE HAT LINING

Application filed February 16, 1931. Serial No. 516,117.

The object of this invention is to provide means for maintaining in good condition a lining or the like within the crown of a hat, said means comprising a sheet of suitable material cut in a predetermined manner, and in accordance with the type of hat to which the additional lining or similar article is applied, this device being retained by the sweat band without separate securing devices, and the material being grease-proof and preventing the soiling of the lining in the manner frequently experienced.

A further object is to provide a lining or the like of one of the commercial types of thin, tough and transparent paper, so that the original lining if of ornamental character will still be visible.

A further object is to provide a lining which shall include a central portion or wall to roughly meet the needs of many types of hats, the lining including also side or wing members the lower edge portions of which are adapted for reception within the sweat band whereby the inner lining will be held in position for the practical or ornamental purposes desired.

In the drawings:

Figure 1 is a view in vertical section, showing a hat of commercial type, and showing in position therein, in dotted line, the protective device herein described, the usual lining for the hat, when employed, being adjacent to the crown and within the structure shown in dotted lines.

Figure 2 is a blank form from which the device is produced.

The crown of the hat is designated 10, the brim is shown conventionally, and the usual lining 12 is the special portion of the article to be protected from foreign material, arising from treatment of the hair, or from perspiration alone.

The protective device comprises a central portion 14 slotted as shown at 14' and 14'', and this central portion is cut away at 15 opposite the adjacent portion of the wings referred to below.

Each protective device includes laterally and downwardly extending members such as are shown especially in Figure 2 and des-

ignated 16 and 17. These devices are preferably cut away at 17', along curved or other lines, and the portions 17', are opposite cut away portions 15, so that reentering open portions are provided in the article considered as a whole, and it is more readily possible to make the device conform to the proportions of the hat.

It is not intended to employ securing devices, for the reason that the edges 16' and 17'' of the wings will be received between the sweat band 18, and the lining 12, and the material will be sufficiently stiff to maintain correct position, and may even be made stiff enough to assist in the shaping of the hat, or in the maintenance of the shape during use; in many instances, one of the commercial types of glassine or cellophane papers will serve the purpose.

What I claim is:

The combination with a soft hat including a depressed crown, a lining and a sweat band, of a self shaping lining-protective member co-extensive at the sides with the lining, and comprising a central portion slotted to permit of conformation with and engagement of the lining adjacent to the depressed middle portion of the crown, said protective member including also wing members connected with the central portion and cut away to form open portions, the edges adjacent the open portions being positioned to underlie spaced elevated portions of the creased soft hat when the outer edges of the wings are positioned within the sweat band of the hat.

In testimony whereof I affix my signature.

GEORGE R. HOPPE.
